ROPE

Stephen A. Reed, Duxbury, Mass., assignor to
Plymouth Cordage Company, North Plymouth,
Mass., a corporation of Massachusetts

Application June 15, 1935, Serial No. 26,708

11 Claims. (Cl. 117—52)

This invention relates to improvements in rope.

More particularly it provides for prolonging the serviceable life of cable-laid rope made of hard vegetable fibre, in which hitherto, under certain conditions of use of the rope in well drilling and the like, internal abrasion has made the rope fail before the surface elements were worn away enough to bring the life of the rope to a normal end.

Rope of the general type to which the invention relates is also sometimes in the trade called hawser-laid rope; and for definition in this description it will be considered that the twisting together of a multiplicity of spun yarns makes a strand; the twisting of three strands together makes a plain-laid rope; and that the twisting together of three plain-laid ropes makes a cable-laid or hawser-laid rope. The successive reversals of direction of twist provide a counter-balancing of the inherent tendencies to untwist, as between the cable, the ropes, the strands, and the yarns.

Ordinarily, cable-laid ropes are harder and stiffer than plain-laid ropes, but they have the defect that when such a rope in service is required to bend around a pulley or the like, it disintegrates and crumbles interiorly, due to the fact that the three plain-laid ropes that compose the cable are interlocked with each other wherever they come together in the interior of the structure.

Assuming that the cable is made of three plain-laid ropes each of which is a three-strand rope, it can be observed that each of these plain-laid ropes has a surface which, as one travels along that surface parallel to the axis, is a series of alternate crests of strands and contlines or valleys between the strands. In the assembling of the three plain-laid ropes to make the cable the crests on any one of these ropes successively come tightly into mesh with the contlines on the other two; and this is a distinct advantage in the process of manufacture because it is comparable to the meshing together of gear teeth and it assures that the component ropes will go into the cable with exact uniformity of length. And it is another advantageous feature that this intermeshing, of each rope with each of the others under severe tension, holds them all locked together and tends to distribute any heavy tensile stress among them instantly and equally. I conceive, however, that the premature interior disintegration results from the same. The intertwining of the three strands of one rope with two other groups of three strands each, each of which strands is full of helixes of spun yarns that are full of helixes of fibres, makes

a multitude and diversity of helixes, such that the cable as whole has greater elasticity than would characterize its individual ropes if pulled straight. When a cable is put to the service of repeatedly lifting and letting fall a heavy tool, there is, in the aggregate, a considerable distance of stretching and of elastic recovery in the rope, as the picking up of the weight tends to lengthen these helixes of elastic fibre and as the releasing of the tension lets them return. As each rope of the cable stands in a helix around the axis of the cable, and the tension is applied in the direction of the axis, it is indeed a fact that the tensile impulse received at one end of the cable is transmitted along the cable by each crest of a strand in a component rope pushing against the adjacent strands of the other two ropes in whose contlines it lies, and by these, in turn, pressing others; and if the cable is not altogether straight but runs over a pulley, the action is nevertheless similar, but with a more obvious localized movement of each strand relative to its neighbors in its associated rope. The tightness of the intermeshing is extreme, but in view of the elastic character and the helical arrangement of the component fibres, I conceive that there is, nevertheless, an ubiquity of movement in the midst of the cable, of each strand relative to its neighbors where it is intermeshed with them. Of course the movement is very slight in dimension; but at these locations the yarns and the fibres of each strand do not lie or move parallel with the yarns and fibres of the neighboring strands with which they are intermeshed. The cross-rubbing makes the friction and abrasion and disintegration which it is an object of the invention to eliminate or reduce. I conceive that this evil is caused by the tightness of the intermeshing, coupled with the complexity of the relative movement of tensile elements, which are severely pressed against each other in the making of the cable, and whose severity of compression toward the axis is immeasurably increased when the cable is under heavy stress of duty, because longitudinal tension tends to straighten all of its helixes and to draw their component substance closer to the axis, and because of the rubbing fibres lying across each other. This makes a complexity of relative movements of tensile elements, engendered by the reciprocating, the slight twistings and untwistings, intermittent stretchings and contractings, the bending and straightenings in passing around a wheel, and the suddenness with which these forces are applied in the particular work of well drilling,—the whole sometimes resulting in a pulverization of spun yarns that are full of helixes of fibres, makes

the interior of the cable before those fibres which are at the exterior become worn away by the abrasion to which the surface of the cable is subject, and therefore before the cable has contributed that quantum of useful service of which it would be capable, were it not for this failure at the interior.

It is therefore an achievement of the invention to relieve the cable of the devastating fibre-against-fibre abrasive action to which cables hitherto normally have been subject.

It is, nevertheless, an object to preserve all of the general features and advantages of cable-laid rope as heretofore customarily formed and organized, and therefore, to accomplish this reduction of abrasion without destroying the elastic properties of the cable, or curtailing its freedom of infinitesimal local movements incidental to normal action, or materially increasing the weight or size 20 of the cable, or decreasing its flexibility.

This is done by introducing a thin flexible fibrous partition which, without seriously affecting the perfection of intermeshing of crests and contlines, takes the wear between fibres at these locations, endures it better than the rope fibres do, and by its own resistance to abrasion defers the time of direct abrasive contact of rope fibres with each other. And it is preferred to enhance the effect by making this partition of a fibrous material which by reason of adsorptive affinity can act as a carrier of a plastic or liquid lubricant so that severe compression of the partition cannot drive all of the lubricant out of it, because a thin film of the lubricant will insistently cling to the fibre.

It is a further feature that the material preferred for the partition is structurally smooth and resistant to abrasion. So long as it lasts this material is what sustains whatever abrasion occurs; but, as it is not itself a tensile element of the cable, 40 its ultimate loss does not reduce the tensile strength.

These results and the other advantages of cables embodying the invention are attained by laying a thin body of soft but wear-resisting material, as fibre cells of practically pure cellulose, of which cotton is an example, between the individual plain-laid ropes which are cabled together to make the cable-laid rope. The extreme pressure with which these ropes are closed together in the 50 making of the cable forces the usual perfect intermeshing of crests and contlines, but actual contacts of strands of one rope with strands of another is prevented by the laying in, at time of the closing of the ropes together, of the said intervening wear-resisting thin body. This may ultimately become worn, by frictional rub of hard fibre elements of the ropes thereon, but so long as it remains it serves the double function of first, holding lubricant, and, second, being the sacrifice 60 to the abrasion, so far as any sacrifice occurs, vicariously for the tensile fibre.

The cotton provides a desirably soft bed for the respective rope elements and has great wear-resisting quality. Its fibrous nature tends to promote distribution of wear through the cotton mass, rather than having it immovably concentrated at particular locations.

The partition may be provided in various ways. One is by means of woven coverings preliminarily applied to the individual ropes, or to the individual strands of the individual ropes. In such case the woven coverings come together at the intermeshed core region, when the ropes are closed together, to provide the partition 70 there; and the portions of these fabric coverings

which are exposed at the exterior of the rope may be trimmed away after the cable is made, or will become worn away in service by ordinary surface abrasion.

The partitioning body may be rendered more 5 resistant to frictional wear by constituting it a carrier of a suitable lubricant, which may be one for which the cellulose of the cotton, or whatever other material may constitute the partition, has a strong adsorptive affinity, so that the extreme compressive forces within the cable will be ineffective for driving out the lubricant except as a relatively slow process.

It is intended that the patent shall cover, by suitable expression in the appended claims, 15 whatever features of patentable novelty exist in the invention herein disclosed.

In the accompanying drawing:

Figure 1 is an elevation of a piece of cable-laid rope embodying features of the invention, 20 one of the component ropes being unlaid to show the intermeshing of crests at the interior of the cable, partitioned in accordance with the present invention;

Figure 2 is an elevation of a cross-section of 25 a cable-laid rope having another embodiment of partitioning means at the intermeshed core region;

Figure 3 is a view similar to Figure 2 with still another embodiment of partitioning means; 30 and

Figure 4 is an elevation of a cross-section of a single one of the component ropes, illustrating how that rope may be covered with a material for constituting a partition; and illustrating 35 also how the individual strands of that component rope may be similarly covered.

Referring to the drawing, three ordinary three-strand ropes, plain-laid, are represented at 10, 12 and 14, twisted together as usual to 40 form a cable-laid rope.

In Figure 1, the component rope 10 has its end portion lifted out of the cable assembly to reveal the manner of intermeshing of crests of the several ropes in the interior region of the 45 cable. The pressure with which these ropes are closed together at the making of a cable is so extreme that the deformities of strands which are represented in the several views are, or may be, produced before the cable-laid rope is put 50 into service. The invention deals particularly with these intermeshings of strands, the tooth-and-hollow character of which is represented at 16 and 28 along the helical bed from which the rope 10 has been removed, and at 26 in 55 the removed rope. These deformities result from the mutual compression of the assembled ropes 10, 12 and 14. Each crest of strand of each rope, at this interior region, becomes settled and wedged into a contline between strands 60 of an adjacent rope. Taking a specific instance for illustration, the strand 18 of rope 10 was fitted into the contline 20 between the strands 22, 24 of rope 12, with deformation of strand 18 clearly shown at 26, where the two places in which the 65 strands 22, 24 were bedded are apparent. Also, in the strand 24, the place of bedding of strand 18 may be seen at 28.

By considering Figure 1 as if the element 30 were omitted it will be apparent how, in the 70 prior ordinary cable-laid rope constructions, there is direct contact and pressure in radial direction toward the axis, of strand surfaces which come together in this meshing, so that any relative movement of the inter-engaged ele- 75

ments in the direction of the axis is frictional, and mutually abrasive, tending toward a pulverizing disintegration of the fibre, under the stresses and strains of service.

The elements of the cable-laid rope of the invention are assumed to exercise as heretofore whatever freedom of movement they have relative to each other, when in use, with the natural elastic stretching and shrinking, of the cable and its sundry helixes of strands and component fibres. But according to the invention the disastrous direct frictional rubbing together of tensile elements incidental to that is eliminated by the introducing of a wear absorbing partition 30 which intervenes between intermeshing parts of the component ropes. This partition may be of any suitable wear-resisting material; but preferably it should be a material which does not abrade the fibre of the ropes. Preferably it should have such smoothness as does not engender abrasion; and it may be a carrier of lubricant. For this I propose a thin body of cotton fibre. Tri-lobed bat sheet form is represented at 30 in Figure 1; and a collapsed tube 25 of woven or knitted cotton yarns is portrayed at 32 in Figure 2. In the thin tri-lobed bat form of Figure 1, the permissibility of some relative movement of cotton fibres among themselves in the bat, as driven by the relative movements 30 of rope fibres with which the surfaces of the bat are in contact, distributes the frictional drag through the body of cotton fibres, in the sheet, thus fractioning the actual length of this short, possibly-abrasive travel into a number of 35 still shorter lengths, absorbing these in the body of cotton, and imposing this travel, ultimately, in these fractions on the introduced fibre, with very little of the wear, due to the movement of one strand relative to another, being imposed on 40 the actual tensile elements. And a suitable lubricant may be carried by the wadding for reducing the abrasion.

Even if the partition 30 or 32 ultimately becomes worn away or extruded, before exterior 45 tensile elements of the rope have become un-serviceable, its presence will at least have deferred the beginning of interior disintegration, at a cost incommensurately small. After that beginning of direct contact of interior elements, 50 the cable-laid rope will be fit interiorly for whatever considerable further period of service such a cable has customarily been capable of until its interior elements become unfit. It is an object of the invention however that the 55 slip-partition 30 will be so selected, as to thickness and organization of its material, that it will ordinarily be sufficiently durable to extend the natural serviceable life of interior elements enough to equal that of surface elements, so that 60 the total service to be extracted from each cable-laid rope may be the total that is warranted by the character of its external contacts.

The cotton batting of Figure 1, or the tubing of woven, braided or plaited cotton of Figure 2, 65 are introduced by feeding this bat or tube as a core element which is laid at the axis around which the three component ropes are being closed in the making of the cable. The element thus being introduced at the core can be 70 formed into the three-vaned or tri-lobed shape by a fixed guide, just before it becomes pinched between the ropes.

In the structure of Figures 3 and 4 this partitioning effect is attained by means of a fabric 75 cover preliminarily applied to the individual

component ropes, as in Figure 3; or the individual strands of each individual rope may be similarly covered as is suggested in Figure 4. The portions of the soft fabric envelope which are subjected to exterior abrasion will become quickly worn away when the finished rope is put into service, leaving the interior compressed portions in their initial locations. Or the exposed exterior web portions of covering may be slit, by cutting them over the helical contours 10 where they are not in close contact with any strand, and the excess material then may be eliminated.

The practice of this invention is not limited to the specific materials or arrangements which are mentioned above as illustrative embodiments, except as may be expressly limited in the claims. Thus, in its broader aspects the invention is not limited to cellulose for the material of the partition; and, if cellulose, it need not be the particular form which grows in nature as fibres of cotton; for cellulose threads and sheets can be made by chemical means, and by extrusions, and, in the form of viscose and the like, may have qualities of smoothness and toughness without the rasping characteristics of manila, sisal and other hard fibres of which cable-laid ropes are made; and it may even be possible that advantage will be found in making the partition of hard fibres, arranged for the slippage 30 to occur in the direction of their length.

So, also, the particular variety of lubricant is a matter of choice among, for example, petroleum and graphite or plumbago or other mineral lubricant, and any lubricants of animal or vegetable origin, especially if being of a nature for which the material of the partition has absorptive affinity.

It will be observed that in the structure described and illustrated the elements are self-retaining. The ropes hold each other, as heretofore; and each wing of the tri-lobular partition is restrained from working out to the periphery of the cable by its being connected across the axis to two similar vanes each of which is firmly pinched,—each will indeed have equally strong reason to move toward its own section of the periphery,—so that the tri-lobed structure tends to hold itself in position. Each sheet-lobe is deeply contorted through its tooth-and-hollow 45 intermeshings, under high pressure, so that it is firmly gripped. In the forms of Figures 2, 3 and 4 the fabric sheet stands in two ply thickness. The greater restriction to which individual fibres become subject when organized in yarns and 50 woven fabric is thus balanced by the freedom of movement which may exist between the two ply, as well as at the surface where each bears against the fibres of rope.

I claim as my invention:

1. A cable-laid rope made of hard vegetable fibre, comprising a plurality of plain-laid ropes twisted together, with the crests of each meshing between crests of others, combined with a thin body of fibrous collapsed-tubular sheet material 65 intervening between intermeshed portions of the ropes thereby relieving intermeshed tensile elements of frictional wear upon each other.

2. A cable-laid rope, comprising a twisted group of intermeshing ropes, constituting tensile elements, each of which is plain-laid, with strands of vegetable fibre constituting crests; each rope of the group having its successive strand crests compressed and deformed so as to fit between successive strand crests of the ropes which ad- 70 75

- join it in the twisted group; combined with a body of non-tensile partitioning material, intervening between rope crests which thus intermesh, for receiving abrasive wear at the intermeshed surfaces when the cable is working, and incapable, due to its non-tensile character, of functioning as a tensile-stress-bearing part of the rope.
3. A cable-laid rope as in claim 2, in which the group consists of three-plain-laid ropes, and in 10 which the partitioning material is of cellulosic composition.
4. A cable-laid rope as in claim 2, in which the partitioning material is of fibrous composition.
5. A cable-laid rope as in claim 2, in which the 15 partitioning material is of unspun cotton fibres laid in sheet form.
6. A cable-laid rope as in claim 2, in which the partitioning material is integrated in self-sus- taining sheet form.
- 20 7. A cable-laid rope as in claim 2, in which the partitioning material is a plurality of sheets over- lying each other.
8. A cable-laid rope as in claim 2, in which the 25 partitioning material is fabricated of cellulosic yarns.
9. A cable-laid rope as in claim 2, in which the partitioning material is combined with a lubri- cant for which the partitioning material has adsorptive affinity.
10. A cable-laid rope as in claim 2, in which the 5 partitioning material comprises entrapped por- tions of sheets of fabric, which sheets, each as a whole, severally enwrap one of the intermeshed tensile elements of the cable.
11. A cable-laid rope as in claim 2, in which the 10 said group consists of three plain-laid ropes, and these three ropes have their crests on their axial sides so deformed that these crests stand in contact with each other in the axial region, except as the said partition intervenes; and in which the said partition is a three-leaved sheet element, ex- 15 tends axially in a curve surfacing the said crests of the axial region, sinuously crossing and re- crossing the axis in following the said deformed 20 surfaces of their intermeshing, and extending out- ward from the axis in sinuous curves following the radial intermeshing of the crests.

STEPHEN A. REED. 25
